Specification for Design.

Patented Nov. 10, 1914.

Application filed May 7, 1913. Serial No. 766,190. Term of patent 7 years.

To all whom it may concern:

Be it known that I, BENJAMIN M. EATON, a citizen of the United States, residing at Boston, in the county of Suffolk and State of Massachusetts, have invented a new, original, and ornamental Design for Stoppers, of which the following is a specification, reference being had to the accompanying drawing, forming part thereof.

In the drawings:—Figure 1 is a top plan view and Fig. 2 a side view of the stopper.

Fig. 3 is a sectional view showing its contour on the plane of its axis, and Fig. 4 is a bottom plan view.

I claim:—

The ornamental design for a stopper as shown.

BENJAMIN M. EATON.
